UNITED STATES PATENT OFFICE.

GEORGE WILKINSON, OF PROVIDENCE, RHODE ISLAND, ASSIGNOR TO GORHAM MANUFACTURING COMPANY, OF SAME PLACE.

DESIGN FOR SPOON AND FORK HANDLES.

Specification forming part of Design No. 7,706, dated August 18, 1874; application filed February 7, 1874.
[Term of Patent 7 years.]

To all whom it may concern:

Be it known that I, GEORGE WILKINSON, of the city and county of Providence and State of Rhode Island, have originated a new design in articles of silver and plated ware, for Spoon and Fork Handles, of which the accompanying photograph, with this specification, is a full and complete description—that is to say, the article spoon and fork

handles substantially as shown in the said photograph.

I claim—

The design for spoon and fork handles, substantially as herein set forth.

GEORGE WILKINSON.
